UNITED STATES PATENT OFFICE.

ROYCE L. BEERS, OF DETROIT, MICHIGAN, ASSIGNOR TO THE UNDERFEED STOKER COMPANY OF AMERICA, OF DETROIT, MICHIGAN, A CORPORATION OF NEW JERSEY.

TUYÈRE STRUCTURE FOR SINGLE-RETORT STOKERS.

Original application filed January 14, 1921, Serial No. 437,238. Divided and this application filed August 11, 1923. Serial No. 656,978.

To all whom it may concern:

Be it known that I, ROYCE L. BEERS, a citizen of the United States, residing at Detroit, in the county of Wayne and State 5 of Michigan, have invented certain new and useful Improvements in Tuyère Structures for Single-Retort Stokers, of which the following is a specification.

My invention relates to a tuyère structure 10 for underfeed stokers and, in some of its features, more particularly to a tuyère structure which may be used in original construction or in repair of the well-known "Jones Standard" stokers. Among the 15 general objects of my invention are to provide a tuyère structure of plate form which is simple, easily manufactured, inexpensive, durable, and of construction enabling the furnace to be operated even if portions of 20 the tuyère-structures exposed to the fuel may burn away.

The tuyère structures ordinarily used in "Jones Standard" stokers are usually made in block form, formed of hollow casting, 25 each adapted singly to be seated in an elongated aperture formed in the furnace floor contiguous to the margins of a retort. Such usual tuyère structure is, of necessity, often subjected to fierce heat and therefore 30 is liable to burning out of its surfaces that are exposed to the fuel. With the ordinary form of tuyère block such burning out is of more serious consequence than that merely of renewal expense. When an exposed wall 35 of the block-formed tuyère structure burns through and gives away, live fuel falls through the opening in material quantity, not only making a hole in the fire but causing an accumulation of burning fuel in the 40 wind chamber below the fire box floor, which of course is destructive to the tie-rods and other parts below the floor level. An improved feature of my invention resides in so constructing the tuyère elements 45 that the burning of an exposed surface of one or more thereof does not result in any substantial dropping of the fire, but limits the injurious consequences to the mere need for replacement of the damaged tuyère element or elements at leisure. Further features of my invention provide for the presentation of a maximum cooling surface to the air-flow passage below the tuyère plates and, for each plate or element, minimized

heat-withstanding surfaces exposed to direct contact with the burning fuel, so as to enable the plate elements to withstand the severe conditions of their use in underfeed stokers. And further my improved plate tuyère structures hereinafter claimed are so 60 constructed and arranged that they may be used in lieu of, or as repair parts to replace, the ordinary block tuyère structures of the Jones underfeed stoker, without requiring change in the arrangement of tuyère 65 receptive openings bordering the retorts.

In the drawings wherein I have shown an embodiment of my invention, Fig. 1 is a plan view with parts broken away, of the marginal portion of a retort and tuyère 70 blocks associated therewith, suitable for Jones Standard stokers; Fig. 2 is a front elevation of the tuyère parts shown in Fig. 1, with the retort margin and some of the tuyère plates broken away; Fig. 3 is a section on line 3—3 of Fig. 2, and Fig. 4 is a perspective detail of a tuyère plate detached.

In the Jones Standard stoker the retort 11 (only fragmentarily illustrated) has a broad rim 12 constituting a substantially 80 horizontal portion of the fire-box floor, and this rim is provided with a series of openings 13 separated from the margins of the retort by the narrow border 14 and separated from each other by narrow strengthening bars 85 15. Each aperture 13 is preferably oblong, and of greatest dimension in a direction parallel with the retort, and for each such opening I employ a plurality of individual tuyère plates 16, say four thereof, in lieu 90 of a single hollow tuyère block. Each of these tuyère plates 16 is a casting comprising the vertical body web 17, a marginal flange 18 extending equally on both sides of the body web along its top and down 95 its rear side margins, a front flange structure 19 interrupted by tuyères or apertures 20 that are formed as faced-opening notches in the flanges, and an attachment base 21, which forms a flangeless extension of the body web 17 and is apertured as at 22 for the reception of the longitudinal tie-rod 23. As shown in Fig. 3, the outline of the tuyère plate, viewed from its face, may be 100 the conventional outline of the ordinary tuyère block; and the tuyère-interrupted flange 19 may take the form of properly spaced shallow ribs 19' extending to dif-

ferent distances rearwardly along the body web, so leaving on each side of the body web 17 a recess or air space vented through the tuyères toward the face of the block and 5 open toward the bottom of the block. The block is preferably so constructed that its two faces, or the face edges of its shallow flanges, lie in two parallel planes substantially at right angles to the axial line of 10 the retort. These tuyère plates are placed in position and anchored by the tie-rods in the fashion shown, and it will be apparent that should the flanges 18 and 19 of the plate burn off, leaving mutilated tuyères 15 burned down (even to the extent of the plates shown in section in the center of Fig. 1) there still is left a substantial grill of fire-supporting web-structure which will prevent the falling through of the fire to any 20 seriously detrimental extent. Furthermore it will be apparent that in effecting repairs, only a minimum number of new parts need be supplied to restore the precise area that has been fire-damaged.

25 Also it will be observed that since the ribs 19' intervening between the tuyère openings are arranged on the side faces of the web 17, so that coring is simple in making the casting, these ribs may be made quite long, 30 to withstand a considerable burning away of the edge of the tuyère which faces toward the retort without enlarging the tuyère- 35 openings, and further that each of the body webs 17, integrally united with the exposed surfaces of the plates, and extending clear down through the receptive orifice 13, acts as a heat conductive element, carrying heat away from the fuel-receptive surfaces of the tuyère, and itself kept cool by constant flow 40 of air through the spaces intervening between adjoining webs. This tends not only to keep the exposed surfaces of the tuyère structure from melting, but by keeping the exposed surfaces quite cool the adhesion of 45 clinkers and slag is minimized, and consequently the chances of clogging the tuyère openings are minimized, so that said openings may be made quite small individually, without disadvantage. Such factors are of 50 substantial importance because, as will be appreciated, the fuel contiguous to the tuyère openings, in underfeed stoker operation, is not only in very active combustion

but also is in intermittent feeding movement and under the fuel weight and the 55 feeding pressure the fuel mass may exert considerable wearing effect on the exposed plate surfaces, and clinker adhesion will both intensify the chance of tuyère plate destruction and detrimentally affect the fuel- 60 feeding action.

I claim:

1. A plate-tuyère element for underfeed stokers comprising in a unitary structure a single, narrow, central body-web of substantially uniform thickness having a wide top portion 17 which affords front, top and rear edges for exposure to the fuel and having a reduced base portion 21 extending below said top portion, all margins of said base portion being of the thinness of the body web; shallow marginal flanges on opposite sides of said upper portion extending uninterruptedly along the top and down the rear thereof; and ribs 19' formed on the 75 sides of said body web and extending substantially horizontally from the front edge of the body rearwardly across the forward portion of the body, these ribs being separated to leave therebetween the tuyère 80 openings 20, and on opposite sides of the body web being identically placed and of the same shallowness as the marginal flanges, substantially as and for the purposes described.

2. The combination with a portion of a fire-box floor providing a retort wall 11 and a retort-bordering rim 12 having oblong openings 13 therethrough, of a plurality of plate tuyère elements mounted in each said opening, and jointly filling the same, each said plate tuyère element comprising a body web having a base portion shaped to fit within the front and rear edges of the opening and having an upper portion above the base portion, each such plate having along its top and rear margins shallow lateral flange projections of uniform extent, and on its side surfaces having ribs of the same depth as said flanges extending substantially parallel to the retort bordering rim and terminating at the front of said body, said flanges leaving therebetween narrow openings, substantially as and for the purposes described.

ROYCE L. BEERS.
